UNITED STATES PATENT OFFICE.

EVARTS G. LOOMIS, OF NEWARK, NEW JERSEY.

BALL-WINDING MACHINE.

1,423,807.

Specification of Letters Patent. Patented July 25, 1922.

Application filed January 6, 1921. Serial No. 435,430.

To all whom it may concern:

Be it known that I, EVARTS G. LOOMIS, a citizen of the United States, and a resident of Newark, county of Essex, and State 5 of New Jersey, have invented certain new and useful Improvements in Ball-Winding Machines, of which the following is a specification.

My invention relates to an improvement 10 in machines for winding balls, and is particularly directed to machines for winding golf balls, an object of the invention being the provision of a machine capable of winding golf balls having a soft center.

15 In my prior Patent No. 1,242,885 of October 9, 1917, I have shown a machine for winding golf balls having a soft center, but in that machine it is necessary to start the winding operation by hand winding the 20 elastic tape upon the center or core until it has been wound sufficiently to enable the ball to be placed in the machine without distorting the core.

The machine of this application is constructed in such a manner that a ball may be wound therein from the outset, means having been provided for so regulating the tension on the tape, etc., that all danger of distortion of the center or core is eliminated.

30 In the accompanying drawings, wherein I have illustrated an embodiment of my invention,

Fig. 1 shows in part sectional elevation a machine of my improved type;

35 Fig. 2 is a view taken substantially on the line 2—2 of Fig. 1;

Fig. 3 is a section taken substantially on the line 3—3 of Fig. 2;

40 Fig. 4 is a plan view of the apparatus of Fig. 2 with portions broken away to show the operating mechanism for the pressing rolls;

Fig. 5 is a view taken substantially on the line 5—5 of Fig. 4;

45 Fig. 6 is a plan view of the mechanism of Fig. 5;

Fig. 7 is a view substantially on the line 7—7 of Fig. 5;

50 Fig. 8 is a sectional view showing the details of the machine broken away at the top of Fig. 2; and

Fig. 9 is a sectional, elevational view of a tensioning device with which my machine is equipped.

55 Referring to the drawings in detail, 1

designates the bed of the machine on which are disposed vertically-extending supports 2 in which is mounted a drive shaft 3. The lefthand end of this shaft as viewed in Fig. 2 carries a broadfaced gear 4 and driving 60 pulley 5, power being supplied to the latter from any suitable source.

On the other end of the drive shaft 1 mount a beveled gear 6 meshing with a beveled gear 7 mounted on a vertically-ex- 65 tending shaft 8, the latter carrying also a pair of cams 9 and 10 and a pinion 11.

Above the drive shaft 3 is mounted a pair of parallel rollers 12 adapted to be moved longitudinally relatively to each other by 70 the cams 9 and 10 already referred to. These rollers are rotated in the same direction and simultaneously by gears 13 meshing with the broad-faced gear 4 already referred to. 75

The shafts on which the rollers 12 are mounted are operatively connected to slides 14, one for each shaft, these slides carrying rollers 15 and 16 adapted to be engaged by the cams 9 and 10 respectively. The cams 80 are set relatively to each other so that as they are rotated they cause the rollers 12 to alternately move to the left as viewed in Fig. 2, the rollers being moved in the the opposite direction by springs 17. 85

Immediately above the rollers 12 are mounted two beveled rotatable bodily movable pressing rolls 18 adapted to engage the ball or core being wound and to not only hold the same in contact with the rollers 12 90 but to impart motion to the ball or core.

The rolls 18 are mounted in housings 19 and are driven through gearing shown best in Figs. 3 and 4 and which will now be described. The rolls are mounted on short 95 shafts 20 and 21 respectively, on each of which is mounted a pinion 22. As the gear train in one housing 19 is a duplicate of that in the other, one only will be described. The pinion 22 meshes with a gear 23 mounted in the housing 19, this gear meshing with a floating gear 24 carried by a triangular-shaped plate 25 mounted on a shaft 26 passing through both housings 19. This shaft carries a gear 27 meshing with the gear 24 and a gear 28 meshing with a gear 29 mounted on the shaft 30 and which shaft carries a large gear 31 meshing with the broadfaced gear 4. As the shaft 26 passes through both housings 19 it will be apparent 110

that rotation will be imparted simultaneously to both rolls 18 and that they will rotate in the same direction.

Owing to the movement to be given the ball or core during the winding operation it is desirable that the rollers 18 be rotated at different rates of speed. To this end I provide the plates 25 and gears 24 already referred to. The plates 25 are pivotally mounted on the shaft 26 and each carries a roller 32 urged into contact with the face of cams 33 by springs 34. The cams 33 are so set that a depression in one cam is opposite to a raised portion in the companion cam. It will be apparent that with the gear train in motion when a roller 32 is engaged by a raised portion on a cam 33, the plate 25 will be rocked about its pivot to carry with it its gear 24. This bodily movement of the gear 24 will accelerate the gear 23 and thereby accelerate the corresponding pressing roller 18. At the same instant a depression in the other cam 33 will be engaging the other roller 32, so that its pressing roll will be given a corresponding negative acceleration.

The housings 19 are pivoted on the shaft 26 so that they may be raised to permit a finished ball to be removed or a new core inserted. The raising or lowering of the housing is accomplished by a foot pedal 36 connected by a suitable link 37 to an upright 38 attached to the housings. The pressure of the rolls upon the ball is readily adjusted by the adjusting member 39.

The mechanism so far described has to do only with the apparatus for handling the ball or core during the winding operation.

Referring now more particularly to Fig. 1 and Figs. 4 to 9 inclusive, it will be seen that the mechanism whereby tape is fed to the core or ball places the tape under tension, this tension being controlled automatically. At the front of the machine I provide three tape-guiding rollers 40, 41 and 42, the latter being preferably of aluminum, the elastic tape 43 with which the ball or core is wound passing from a supply roll over a fixed trough-shaped guide 44, over guide roller 40, under guide roller 41 over guide roller 42 to the ball or core 45. The roller or drum 40 is provided with a brake-band 46, the tension of which is adjustable by the adjusting mechanism 47. The roller 41 is rotatively supported on a stud shaft 48 carrying differential gearing comprising an externally-toothed gear 49 meshing with a pinion 50 mounted on a stud shaft 51 to which the guide roller 42 is secured. Keyed to the gear 49 is a small gear 52 also rotatively supported on the stud shaft 48, this gear meshing with a pair of floating gears 53 connected to each other by a member 54 which is keyed to the roller 41, these gears in turn meshing with an internally-toothed gear 55. The latter is provided with a lateral flange

56, adapted to be engaged by a clamp plate 57. The latter is suitably mounted in the housing 58 enclosing the differential gearing upon a stud shaft 59 which is moved to the right as viewed in Fig. 7 by a cam 60. The latter is given a partial rotation at the desired instant through a connection 61 and 62 with a cam 63 driven by a gear 64 meshing with a pinion 11 already referred to. The roller 41 has operatively attached to it the tension regulating device shown in Fig. 9.

Secured to the gear 49 and extending laterally with respect to the roller 41 is a drum 65, this drum being secured to the gear 49 by screws 66. Cooperating with and partially surrounding this drum 65 is a brake band 67, one end being secured at 68 while the other end is flexibly secured at 69 to one arm of a bell-crank lever 70 carrying at one end an adjusting screw 71 adapted to bear upon the surface of the housing 58 whereby the tension of the brake band 67 on the drum 65 may be adjusted.

In operation a turn of tape is taken around a core 45 and the core then inserted in the machine upon the longitudinal movable rollers 12, the pressing rolls 18 being moved upwardly by depressing the foot pedal 36. If the machine is now set in operation the rollers 12 will be driven and also be moved longitudinally relative to each other, and the pressing rolls 18 will be rotated at the same time at different variable speeds. The core due to these movements of the rollers 12 and the pressing rollers 18 will be rotated about a horizontal and a vertical axis, the peripheral speed of rotation of the core about the horizontal axis being practically uniform while the motion of the core about the vertical axis is irregular, varying in both speed and direction due to the shape of the cams 9 and 10 and the cams 33, resulting in a practically uniform distribution of the tape on the core and the production of a substantially spherical ball.

At the start of the winding operation the cam 63 is in position to cause the link 61 to actuate the cam 57 into engagement with the flange 56 of the internal toothed gear to retard the same. At this time also the tension device illustrated in Fig. 9 operates to retard the rotation of the roller 41 to thereby retard the rotation of the roller 42. The result of this retarded motion of the roller 42 is to cause the tape 43 to be placed under tension and owing to the curvature of the roller 42 which roller is preferably made of aluminum the tape will be stretched laterally so as not to deform the core.

It will be apparent that the core is driven about both a horizontal and a vertical axis from four points, to-wit; the two points of contact of the rollers 12 with the core and the two points of contact of the driven press-

ing rolls 18 with the core, thereby enabling me to apply tape to a soft core without distorting the core.

While I have described an embodiment of my invention, it is to be understood that the apparatus herein described may be changed within the purview of my invention.

What I claim is:

1. The method of winding a core which 10 method consists in driving a core from a plurality of points to cause the core to rotate about one axis, driving the core about a plurality of other points to cause the core to rotate about another axis and varying the 15 speed and direction of rotation of the core about one of said axes.

2. The method of winding a core which 20 method consists in driving the core from a plurality of points to cause the core to be rotated about one axis and driving the core from a plurality of other points about another axis.

3. The method of winding a core which 25 method consists in driving a core from a plurality of points about a horizontal axis at practically a constant peripheral speed and from a plurality of other points about another axis at a variable speed.

4. In a machine of the class described, 30 the combination of parallel rollers movable longitudinally relatively to each other, means for rotating said rollers, and driven means for driving a ball or core and for pressing the same into engagement with the 35 said parallel rollers to cause the ball or core to be driven by the parallel rollers and the said driven means.

5. In a machine of the class described, the 40 combination of a pair of driving rolls for driving a ball or core to rotate the same about a horizontal axis, means for driving the ball about a vertical axis and means for varying the rate at which the ball or core is rotated about one of said axes with respect to the 45 rate at which it is rotated about the other of said axes.

6. In a machine of the class described, the 50 combination of means for driving a ball or core from a plurality of points to rotate the same about a horizontal axis, means for driving the ball or core from a plurality of other points to rotate the same about a vertical axis, and controlling means for the ball driving mechanism to vary the rate and direction of rotation of the ball or core about the vertical axis with respect to its rotation about a horizontal axis.

7. In a machine of the class described, the 60 combination of a plurality of driven rollers, a plurality of driven rolls, said rollers and rolls being arranged relatively to each other to receive a ball or core and drive the same about two axes substantially at right angles to each other, and means for varying the 65 speed of said rolls to vary the rate of rota-

tion of the ball or core about one of said axes with respect to its rotation about the other of said axes.

8. In a machine of the class described, the combination of a plurality of driven 70 rollers having longitudinal relative movement, a plurality of driven rolls, said rollers and rolls being positioned relatively to each other to receive and drive a ball or core about a horizontal axis and a vertical axis, 75 means for varying the speed of said rolls to vary the rate of rotation of the core about the vertical axis.

9. In a machine of the class described, the combination of a plurality of driven rollers, 80 a plurality of driven rolls, said rollers and rolls being arranged relatively to each other so as to simultaneously drive a ball or core, the latter being driven about two axes substantially at right angles to each other, and 85 means for varying the speed of the said rolls to cause a corresponding variation in the speed of rotation of the ball or core.

10. In a machine for winding balls or 90 cores, the combination of a plurality of rollers movable longitudinally relatively to each other, a pair of independently rotatable rolls, said rollers and rolls being arranged to receive a ball or core and drive the same about two axes substantially at right angles 95 to each other, and means for varying the relative speeds of the rolls to cause the speed of rotation of the ball or core about one of said axes to be varied.

11. In a machine for winding balls or 100 cores, the combination of a pair of driven rollers and a pair of driven rolls, said rollers and rolls being arranged to engage simultaneously and drive a ball or core about a plurality of axes, gearing for driving said 105 rolls, part of said gearing being movable bodily to vary the speed of rotation of the said rolls to cause the motion of the ball or core to be varied.

12. In a machine for winding balls or 110 cores, a pair of driven rollers adapted to receive a ball or core between them and to drive the same, a pair of driven rolls above the said rollers for also driving the ball or core and to maintain the same in 115 driving engagement with the said rollers, gear trains for driving the said rolls, and means for imparting bodily movement to a gear of each train to cause the speed of relative rotation of the rolls to be varied 120 to correspondingly vary the movement of the ball or core.

13. In a machine for winding balls or 125 cores, a pair of parallel longitudinally movable driven rollers, a pair of tapered driven rolls above the said rollers, said rollers and rolls being adapted to simultaneously contact with a ball or core to drive the same, a drive for said rolls and means operable automatically for varying 130

the relative speeds of said rolls to cause the movement of the ball or core to be varied.

14. In a machine for winding balls or cores, a pair of parallel longitudinally movable driven rollers, rolls above said rollers, said rollers and rolls being arranged to engage and drive a ball or core, gears for driving said rolls and cam mechanism for imparting bodily movement to certain of said gears to cause the movement of the ball or core to be varied.

15. In a machine for winding balls or cores, parallel longitudinally movable driven rollers and driven rolls for receiving a ball or core to rotate the same about two axes at right angles to each other, and means for automatically varying the relative speeds of the driven rolls to vary the motion of the core about one of said axes, both as to speed and direction of rotation.

16. In a machine for winding balls or cores, a parallel longitudinal movable driven roller and driven rolls for receiving a ball or core to rotate the same about two axes substantially at right angles to each other, means for supplying tape to a ball or core driven by said rollers and rolls, guiding means for said tape, means for driving said rollers, and a tension device automatically controlled by said driving means for controlling the tension on the tape as the same passes to the core or ball.

17. In a machine for winding balls or cores, parallel longitudinal movable rollers and a pair of rolls for receiving a ball or core and to rotate the same about a horizontal and a vertical axis, means for automatically controlling the rotation of said rolls to vary the motion of the core, means for supplying tape to a ball or core as the

same is being rotated by said rollers and rolls, driving means for the said rollers and a tension device automatically controlled by said driving means for regulating the tension on the tape as the same is fed to a ball or core being rotated by said rollers and rolls.

18. In a machine for winding balls or cores, rollers and rolls for receiving a ball or core and for driving the same about a vertical and a horizontal axis, means for automatically varying the motion of the ball or core about a vertical axis, both as to speed and direction of rotation, a pair of guiding rollers between which tape is led to a ball or core in the winding operation, one of said guiding rolls being shaped to cause the tape in passing over the same to be stretched laterally and differential gear mechanism connected to this last-named roll and under the control of the driving mechanism for the rollers first mentioned whereby the tension on the tape as it is wound upon the ball or core is automatically controlled.

19. In a machine for winding balls or cores, rollers and rolls adapted to receive a ball and rotate the same about a horizontal and a vertical axis, means for supplying tape to a ball or core as the same is being so rotated, guide rollers over and under which the tape is led in passing to the ball or core being wound, differential gearing automatically controlled for varying the tension on the tape as the same is passed to the ball or core being wound and an adjustable brake for said gearing.

This specification signed this 31st day of December, 1920.

EVARTS G. LOOMIS.
